NONCLOGGING BIN STRUCTURE

Wyman Eaton, Chicago, Ill., assignor to Freyn
Engineering Company, Chicago, Ill., a corpora-
tion of Maine

Application March 4, 1944, Serial No. 525,065

7 Claims. (Cl. 222—506)

1

The present invention relates to improvements in non-clogging bin structures.

More particularly the present invention relates to improvements in bin structures such as are used for supplying materials to scale cars such as used in connection with blast furnaces or analogous structures. The bins are ordinarily elongated parallel to the direction of movement of the scale cars and are provided with a plurality of gates spaced along the width of the bin structure for controlling the delivery of material to the cars. It is desirable that each bin gate be of only moderate length for convenience in discharging measured quantities of material and also for convenience in operation and control. The full width of the bin is divided into perhaps four gates, more or less. Difficulties have arisen in bin structures in common use due to the fact that the sloping floors of the bins have been provided with hinge structures for the gates, forming relatively wide obstructions, rather closely spaced from one another, permitting the arching of material between the obstructions. This arching adds to the difficulty of discharging the materials, requires manual labor, and is undesirable.

An object of the present invention is to provide a gate-controlled bin structure presenting a minimum of obstruction to the flow of material therefrom.

A further object is to provide a bin structure having a swinging gate, the fulcrum means for said gate being located out of the path of material in the bin structure.

A further object is to provide a bin structure which is sturdy and relatively simple in construction and presents a minimum of opportunity for the material within the structure to arch across between obstructions.

A further object is to provide a bin structure in which the problems of maintenance and servicing are minimized.

A further object is to provide a bin structure having a sloping discharge wall and a plurality of pairs of gates for controlling discharge along said wall in which the fulcrum means for said gates are protected from such discharge by fulcrum protecting members which divide such discharge into a plurality of paths each controlled by a pair of gates.

A further object is to provide a bin structure having a lifting gate provided with projecting means adapted to be lifted by operating means carried by a scale car or the like wherein the danger of damage is minimized in the event that

2

said scale car or the like should strike said projecting means while the scale car is in motion.

A further object is to provide a bin structure having a gate provided with projecting means adapted to be engaged by a lifting member, said lifting member being yieldable whereby to avoid damage in the event that it should be struck by any portion of a moving scale car.

A further object is to provide a bin structure well adapted to meet the needs of commercial operation.

Further objects will appear as the description proceeds.

Referring to the drawings—

Figure 1 is a fragmentary view in side elevation of one embodiment of the present invention showing a plurality of bin gates;

Figure 2 is a sectional view taken along the plane indicated by the arrows 2—2 of Figure 1;

Figure 3 is a sectional view taken along the curved surface indicated by the arrows 3—3 of Figure 2;

Figure 4 is a sectional view taken along the planes indicated by the arrows 4—4 of Figure 2;

Figure 5 is a sectional view taken on the same plane as Figure 4 but illustrating on a larger scale certain fulcrum mechanism associated with the bin gates;

Figure 6 is a sectional view somewhat similar to Figure 2 but illustrating a modified construction.

Figure 7 is a fragmentary view in section taken along the planes indicated by the arrows 7—7 of Figure 6; and

Figure 8 is a view in elevation taken in the direction of the arrows 8—8 of Figure 6, the lifting member on the scale car being located, however, at a level where it strikes a yieldable projection on a bin gate as said scale car travels along parallel with the width of the bin structure.

Referring first to Figures 1 to 5, the numerals 10 and 11 indicate the sloping walls of a bin leading to a throat indicated by the numeral 12. The outer boundary of this throat, adjacent to the wall 10, is defined by the rail 13, which is shown in inverted position. Spaced downwardly and outwardly from the rail 13 is the rail 14. Both of said rails are fast with respect to the walls 10 and 11. The space between the rails 13 and 14 permits access to the interior of the bin from the outside thereof. The angular relationship between the locations of the rail 13 and the rail 14 will be such that there will be no tendency for material within the bin to escape

therethrough. However, the space between the rails 13 and 14 may be closed, if preferred, by a closure means, preferably removable.

Disposed along the width of the bin, that is—transversely of the bin structure as illustrated in Figure 1, are a plurality of housing members or fulcrum protecting members 15—15 having the side walls 16—16 and the top walls 17. The top walls 17—17 of the housing members 15 are securely fastened to the bottom portion of the rail 14.

The housing members 15—15 provide receptacles for the swinging arms of the bin gates, and also accommodate fulcrum means for said swinging arms, all of which will be described presently. The housing members 15—15 open downwardly and outwardly, and their side walls 16—16, with their top walls 17, divide the throat 12 of the bin into a plurality of bin openings or passageways 18 each controlled by swinging gate structure which will now be described.

The sloping floor 11, except where it is interrupted by the housing members 15—15, provides a continuous sloping surface for facilitating the flow of material from the bin through the openings 18—18. Each of these bin openings 18 is controlled by a double gate mechanism including the inner swinging gate 19 and the outer swinging gate 20. These two gates 19 and 20 have a common axis of swing, indicated by the numeral 21. Preferably the axes of swing of all of the pairs of gates 19 and 20 cooperating with the same sloping wall 11 will be disposed in line.

The two gates 19 and 20 associated with each opening 18 cooperate with each other to perform the well known function of double gate structures, of insuring the stoppage of flow of material even though one of the gates should be closed upon a lump of material and should therefore be held partially open, as explained in the patent to Hayes No. 1,525,236.

The inner gate 19, which is of arcuate cross-section having its axis coincident with the axis 21, includes two swinging arms 22—22. Each of the outer gates 20 includes two swinging arms 23—23. A swinging arm 22 of one inner gate 19 and a swinging arm 22 of the next adjacent inner gate 19 are located to swing within the same housing member 15. A swinging arm 23 of one outer gate 20 and a swinging arm 23 of the next adjacent outer gate 20 are also located within the same housing member 15. This is clearly illustrated in Figures 1, 4 and 5. The adjacent swinging arms 22—22 of adjacent inner gates 19 and the adjacent swinging arms 23—23 of adjacent outer gates 20 are swingingly mounted upon a cylindrical member 24, bushings 22a and 23a being provided to reduce friction. Each member 24 is carried by a pair of lugs 25—25 fast to the supporting structure of the adjacent sloping wall 11. A keeper 26 is provided for securing the cylindrical member 24 against either longitudinal or rotative movement relative to the lugs 25—25.

Each inner gate 19 is provided, adjacent to each of its side extremities, with a reinforcing angle 26 and a lug 27. The lugs 27—27 at the two extremities of each inner gate 19 are adapted to be engaged on their under sides by the swinging arms 23 of the corresponding outer gate 20. Said lugs 27—27, as shown in Figure 2, are disposed at a materially higher level than the plane bounding the upper extremities of the swinging arms 23—23 of the corresponding outer gate 20, so that when an outer gate 20 is raised the lifting of the corresponding inner gate 19 will occur after

the outer gate 20 has risen through a material distance. When the outer gate 20 is lowered, the inner gate 19 will close before the outer gate 20 closes.

5 The swinging arms 23—23 of the gate 20 preferably take the form of channels. The closure portion of the gate 20 is made up of the channel 28 and the angle 29. Mounted upon the inner side of the channel 28 is the bracket 30, which 10 includes the two arms 31—31 spaced apart and supporting the roller 32.

The numeral 33 indicates an arm which may be carried by a scale car or other receptacle for receiving material from the bin. The arm 33 15 may be raised or lowered by mechanism not illustrated. Such mechanism is well known to those skilled in the art and need not be described in detail.

The mode of operation of the above described 20 embodiment of the present invention will be clear without detailed explanation. When the inner gate 19 and the outer gate 20 of any pair of gates are both in their lowermost positions, the corresponding opening or passageway between the 25 housing members 15—15 will be effectively closed. When it is desired to permit the flow of material from the bin past any one of the double gate mechanisms, the arm 33 will be raised and will engage the roller 32, exerting a lifting force to 30 the outer gate 28. After the outer gate 20 has been raised a predetermined distance, the swinging arms 23—23 thereof will engage the lugs 27—27 of the inner gate 19, whereby further lifting movement of the arm 33 will result in the 35 raising of both gates. The gate 19, as shown in dotted lines in Figure 2, may be raised up to a region where the upper edge of said gate 19 is in proximity to the rail 13. Material from the bin will flow down through the openings 18—18 between the housing members 15. The top walls 17—17 of the housing members 15—15 will not be effective to retain any considerable amount of material flowing down from the sloping wall 11, and will not provide effective abutments for arching of material thereacross. In the event, however, that any such arching should occur, it would be a simple matter for a workman, after the gates have been lowered, to insert a tool through the space between the rails 13 and 14 to 45 break such an arch.

The fulcrum means for each of the gates 19 and 20 is located out of the flow of material in the bin, so that said fulcrum means will not become clogged with such material, and, of course, 50 present no obstructions for the undesirable arching of such material. The gate means move in an arc disposed entirely above said sloping bottom wall but said gate means are fulcrumed upon means disposed below the sloping bottom wall. The arrangement is such that there is no interruption in the floor of the bin or passage, since the fulcrum is disposed at the two sides of each gate in an intermediate region between adjacent gates.

65 According to the construction illustrated in Figures 6, 7 and 8, the bracket on the outer gate is yieldable longitudinally of the bin structure, that is—along the line of movement of the scale car.

Referring to Figures 6, 7 and 8, a scale car is indicated by the numeral 35a, which scale car is provided with the lifting arm 36. Said arm 36 takes the form of a bracket carrying a short roller 37, the roller 37 being adapted to engage the under side of the bracket 34 when a lifting force is to be 70 exerted upon the outer gate 20a. Said bracket 34

has a portion 38 adapted to have a sliding movement against the rear side of the channel 28. Said channel 28 is provided with the arcuate slot 39 for receiving a pair of outstanding studs 40-40 carried by the portion 38 of the bracket 34. A pair of nuts 41-41 are carried by the studs 40-40 and are adapted to frictionally hold the bracket 34 in right-angular relationship with the adjacent portion of the outer gate 20, as illustrated in Figures 6, 7 and 8.

The structure illustrated in Figures 6, 7 and 8 has the advantage that if the bracket 34 should be in position to be struck by the bracket 36 carried by the scale car when said scale car is moved, no destructive effects would result, the bracket 34 merely yielding in a swinging movement about the pivot line 35 to allow the passage of the bracket 36. The bracket 34 may then be moved back to its proper right-angular position with respect to the channel 28, the nuts 41-41 being turned down to yieldably hold the bracket 34 in this position.

The construction illustrated in Figures 6, 7 and 8 has the further advantage that the lifting force will, in practice, be applied to the outer gate 20a always in the same position symmetrically disposed with respect to said gate for the reason that the bracket 34 will be located symmetrically with respect to said gate. This will occur without careful spotting of the scale car carrying the bracket 36. It is more important, generally, to have this lifting force symmetrically disposed with respect to the outer gate 20a than to have the region of contact symmetrically placed with respect to the roller 31.

Though certain preferred embodiments of the present invention have been described in detail, many modifications will occur to those skilled in the art. It is intended to cover all such modifications that fall within the scope of the appended claims.

What is claimed is:

1. In bin structure, in combination, a sloping wall having slots at its lower edge, housing members of inverted U-shaped cross-section covering said slots and dividing said wall into a plurality of discharge passageways, gate means for controlling said passageways, and fulcrum means for swingingly mounting said gate means, said fulcrum means being located below the plane of said sloping wall, the side portions of said gate means being located in said housing members, said gate means having an arc of movement disposed entirely above said sloping wall.

2. In bin structure, in combination, a sloping wall having slots adjacent to its lower extremity, housing members of inverted U-shaped cross-section covering said slots and dividing said wall into a plurality of discharge passageways spaced apart by said housing members, and gate means for controlling each of said passageways, said gate means including swinging side members, adjacent swinging side members of adjacent gate means being located within one of said housing members, the fulcrum means for said swinging members being located below said sloping wall.

3. In bin structure, in combination, a sloping wall having slots adjacent to its lower extremity, housing members of inverted U-shaped cross-section covering said slots and dividing said wall into a plurality of discharge passageways spaced apart by said housing members, and gate means for controlling each of said passageways, said gate means including swinging side members, adjacent swinging side members of adjacent gate

means being located within one of said slots, said swinging members having fulcrum means located below the plane of said sloping wall, the side portions of said gate means being located in said housing members, the range of movement of said gate means being entirely above said sloping wall.

4. In bin structure, in combination, a sloping wall, housing members of inverted U-shaped cross-section dividing said wall into a plurality of discharge passageways, and gate means for controlling each of said passageways, said gate means including swinging side members, adjacent swinging side members of adjacent gate means being located within one of said housing members, said adjacent swinging members having common fulcrum means located below the plane of said wall, the side portions of said gate means being located in said housing members, the range of movement of said gate means being entirely above said sloping wall.

5. In bin structure, in combination, a sloping wall having slots in its lower extremity, and housing members of inverted U-shaped cross-section covering said slots and dividing said wall into a plurality of discharge passageways, each of said passageways being controlled by a gate assembly, each gate assembly including two gates in series with each other, one of said gates being provided with abutment means adapted to be engaged by the other of said gates after said other gate has been lifted throughout a predetermined region, adjacent portions of adjacent gate assemblies being located within one of said slots, said adjacent portions having common fulcrum means located below the plane of said sloping wall, the range of movement of said gate means being entirely above said sloping wall.

6. A bin structure including a sloping wall having slots in its lower extremity, another wall opposite to said sloping wall, a plurality of housing members of inverted U-shaped cross-section covering said slots and dividing said sloping wall into a plurality of passageways for the discharge of material, said other wall having an opening therein located above said housing members whereby access may be had to the interior of said bin to remove deposits of material from said housing members, and gate means independently controlling said discharge passageways, adjacent portions of adjacent gate means being swingingly disposed within a common housing member, said gate means having fulcrum means located below the plane of said sloping wall, the range of movement of said gate means being entirely above said sloping wall.

7. A bin structure including a sloping wall having slots in its lower extremity, another wall opposite to said sloping wall, a plurality of housing members of inverted U-shaped cross-section covering said slots and dividing said sloping wall into a plurality of passageways for the discharge of material, said other wall having an opening therein located above said housing members whereby access may be had to the interior of said bin to remove deposits of material from said housing members, and gate means independently controlling said discharge passageways, adjacent portions of adjacent gate means being swingingly disposed within a common slot, said gate means having fulcrum means located below the plane of said sloping wall, the range of movement of said gate means being entirely above said sloping wall, said opening in said other wall being defined by two parallel structural steel members spaced apart, the lowermost of said structural

steel members being spaced outwardly with respect to the uppermost of said structural steel members whereby to minimize the tendency of material within said bin structure to escape therebetween.
